CAVITY RESONATOR DEVICES

Bruce B. Cork, Peck, Mich., and Melville Clark, Jr., Santa Fe, N. Mex., assignors, by mesne assignments, to the United States of America as represented by the Secretary of the Navy

Application December 27, 1945, Serial No. 637,427

2 Claims. (Cl. 333—13)

This invention relates to a transmit-receive assembly for use in a radiant energy system where it is desired that a common antenna be used for transmission and for reception of energy.

This invention further relates to a transmit-receive assembly characterized by a compact physical structure adapted to be easily manufactured.

This invention additionally relates to a transmit-receive device comprising a double-tuned resonant circuit, each circuit consisting of a resonant cavity with coupling means between cavities such that a uniform frequency response band is obtained over the tuning range of the cavities.

The invention will be described below with reference to the accompanying drawings in which,

Fig. 1 illustrates in perspective the transmit-receive assembly partially broken away to reveal the interior;

Fig. 2 illustrates a cross sectional view of the assembly of Fig. 1 taken along line 2—2 of Fig. 3, incorporating certain minor modifications and additions;

Fig. 3 is an end view partially in section, taken along line 3—3 of Fig. 2; and

Fig. 4 is a top view of the assembly of Figs. 2 and 3, with one of the input connectors broken away better to illustrate the interior construction thereof.

Fig. 5 is a fragmentary perspective view of an alternate embodiment of the invention.

Referring to Fig. 1, the transmit-receive (TR) assembly is shown comprised of a plurality of walls 10, 11, 12 and 13 made of a conducting material and forming a rectangular cavity. The right-hand end of the cavity is open, forming a large rectangular iris 14, through which energy from a transmitter oscillator (not shown) may be coupled into the cavity. Within the cavity, in region adjacent iris 14, a vertical conducting post 15 is anchored to the floor 13 of the cavity. At its upper end post 15 bends abruptly and emerges through a hole 16 in wall 11 of the cavity to become the inner conductor 17 of a concentric transmission line, having inner conductor 17 and outer conductor 20. Concentric transmission line 17—20 is adapted to be connected to the feed line of an antenna (not shown) capable of radiating and receiving energy.

In a region adjacent antenna coupling post 15, and opposite from iris 14, a first TR resonant circuit is located. This circuit utilizes an elongated conductor 21 connected at its upper end to wall 12 of the cavity and extending downward into the cavity. Conductor 21 cooperates with the walls of the cavity to form a resonant line tunable to the incoming energy coupled from the antenna to post 15. At the end of conductor 21 remote from wall 12, is connected a TR tube 22. Tube 22 is a known form of device normally presenting a high impedance between conductor 21 and wall 13, but capable of breaking down to short-circuit this end of the resonant circuit.

Tube 22 may be a commercial type tube having a pair of terminals 23, 24 (Fig. 2), connected respectively to the end of conductor 21 and to wall 13. A gaseous path within tube 22 normally presents a high impedance between terminals 23 and 24. When, however, a high volt-

2

age, exceeding a critical value, is applied between conductor 21 and wall 13, tube 22 will become conducting, greatly decreasing the impedance between terminals 23 and 24 and detuning the normally resonant circuit comprised of inner conductor 21 and the walls of the cavity. To maintain ionization within tube 22 at a required minimum level, a keep-alive potential is continuously applied between a third terminal 25 and terminal 24. This potential is sufficiently large to maintain ionization within tube 22 at a point such that the tube will break down rapidly upon application of high voltage, but is insufficient to lower the impedance appreciably in the absence of a high breakdown potential between terminals 23 and 24.

A second resonant circuit is located adjacent the resonant circuit of conductor 21 and opposite from antenna input post 15. This circuit comprises inner conductor 27 attached at its upper end to wall 12 of the cavity. Electrically it is the full equivalent of conductor 21 with the exception that a TR tube is not connected between its end and wall 13.

Together conductors 21 and 27 comprise a double tuned resonant circuit forming a wide pass band for the translation of incoming energy from antenna post 15. The pass band characteristic is determined by the coupling between the two conductors 21 and 27, which in turn is determined by the nature of a conducting member 30 anchored at its lower end to wall 13 and located between the conductors 21 and 27. In Fig. 1 conducting member 30 is shown as a conducting wall extending horizontally from wall 10 to wall 11 of the cavity and extending upward into the cavity approximately half way toward wall 12. In the transmit-receive assembly illustrated in Fig. 1, the band pass characteristic of the resonant circuits formed by conductors 21 and 27 is determined largely by the height of wall 30.

The mid-point frequency of the pass band may be varied over a considerable range by tuning the cavity with tuning slugs 31 and 32 applied respectively to inner conductors 21 and 27. Slugs 31 and 32 are conducting members which contact neither their respective inner conductors nor the cavity walls. Tuning is effected by varying the position of the slugs along the respective conductors, thereby varying the electric and magnetic fields within the cavity and resulting in a variation in resonant frequency of the double tuned circuit. In the embodiment shown in Fig. 1, slugs 31 and 32 are supported by a common non-conductive cross member 33 movable axially along conductors 21 and 27 by means of a rod 34 extending through wall 12 of the cavity. Adjusting rod 34 may be either conductive or non-conductive.

Next to conductor 27 of the double tuned TR circuit, and opposite from conductor 21, is located a coupling post 35, in general similar to coupling post 15 previously described. Post 35 is used to apply energy from the cavity to an intermediate frequency detector not shown.

The left-hand end of the cavity, remote from iris 14, is closed by a conducting wall 36. An iris 37 is cut in wall 36, providing coupling between the left-hand end 60 of the cavity and a local oscillator cavity shown partially at 40. A portion of the local oscillator is shown at 41. It will be understood that any form of oscillator may be used at the left-hand end of the cavity.

Fundamentally the operation of the TR assembly constituting this invention is as follows. When the transmitter oscillator is in operation, energy is coupled to the cavity through iris 14 and to the coupling post 15, from which it is fed through concentric line 17—20 to an antenna. This high-level transmitter energy will also appear along conductor 21. The high voltage will break down tube 22, causing a virtual short-circuit to appear between the end of conductor 21 and wall 13. This will

substantially detune that portion of the cavity so that only a small portion of the transmitter energy will be coupled to conductor 27 and thence to the I. F. post 35 and local oscillator 41. The I. F. crystal will thus be protected from burning out at the high level of the transmitter energy.

Energy received by the antenna, when the transmitter is not in operation, will be applied to the cavity through post 15. Some energy will be coupled through iris 14 to the transmitter oscillator but this will be small because the transmitter, when not energized, will be detuned from the frequency of the incoming energy.

Accordingly the greater part of the energy will be coupled from post 15 to conductor 21. Conductors 21 and 27, comprising double-tuned resonant circuit, will pass the energy with minimum attenuation to the I. F. coupling post 35, where it will be mixed with local oscillator energy coupled through iris 37 and taken out of the cavity for application to an intermediate frequency detector.

If it is desired to operate the transmit-receive assembly in a different frequency range, tuning rod 34 may be moved to alter the position along the frequency spectrum of the mid-point of the pass band of the double-tuned resonant circuit comprising conductors 21 and 27.

In order to adjust the circuit so that the tuning of line 27 will have the desired relation to that of line 21, a hollow screw 42 may be inserted immediately below the end of conductor 27, forming a variable capacitive load, which may be adjusted until proper operating characteristics are obtained.

When the equipment is not in use, the keep-alive voltage will be shut off from the TR tube 22. Under such circumstances, if high level energy should be received by the antenna and applied to coupling post 15, it might be transmitted through the TR to coupling post 35 damaging the I. F. detector and/or local oscillator. Under such conditions, a conducting rod 43 may be slid within hollow screw 42 until it touches the end of conductor 27. This portion of the cavity will then be short-circuited, constituting to an augmented extent, the same type of protection as is provided during operation by the TR tube 22.

The assembly shown in Figs. 2, 3, and 4 is substantially the same as shown in Fig. 1 with the following modifications. In the first place, a special tuning means has been shown for actuating the tuning rod 34 of Fig. 1. The action of this tuning means will be quite obvious by reference to Fig. 2. Additionally, tuning slugs 31 and 32, shown as homogeneous conducting members in Fig. 1, have been replaced by a single, integral non-conductive member 50 attached in the center to tuning rod 34. At high frequency, current is confined to the surface of a conductor, and it is possible to use a slug in the form of a toroid of non-conductive material coated with a conductive material such as silver. In Fig. 2, tuning member 50 comprises a pair of toroids of non-conductive matter coated with a layer of silver as shown at 51.

With these exceptions the assembly of Figs. 2, 3 and 4 is substantially the same as that of Fig. 1, and the same reference numerals have been applied to corresponding parts.

It has been found that conducting wall 30 of Fig. 1 may be replaced by a screw 60 (Fig. 5) extending upward into the cavity from floor 13. By proper proportioning of the screw, it has been found that the desired coupling may be maintained, and at the same time a certain degree of discrimination against an undesired harmonic, such as the third harmonic, may be obtained. If desired, coupling screw 60 may extend inward from either wall 10 or wall 11, instead of upward from floor 13. Also, under certain conditions a plurality of screws may be substituted for wall 30 of Fig. 1.

While the coupling between the several members within the cavity has been shown as a large iris, equal to the

cross section of the cavity, it will be understood that, if desired, the coupling between members may be varied by use of a wall such as wall 30, or by coupling screws such as screw 60, or by use of a small iris such as iris 37.

It will be further understood that this invention is not limited to iris coupling between the portions of the circuit; loop coupling or capacitive coupling may be employed where appropriate.

It will be further understood that any form of transmitter, local oscillator, I. F. detector or antenna may be employed in connection with the transmit-receive assembly of this invention.

Although we have shown and described certain specific embodiments of the invention, we are fully aware of the many modifications possible thereof. This invention is not to be restricted except insofar as is necessitated by prior art and the spirit of the disclosure.

What is claimed is:

1. A double-tuned resonant circuit comprising a plurality of conducting walls forming a cavity, a first elongated conductor connected at one end to a first cavity wall and extending into the cavity, a second elongated conductor connected at one end to said first cavity wall and extending into the cavity, an intermediate conductor connected to a cavity wall opposite said first cavity wall and extending into the cavity between said first and said second elongated conductors, a pair of conducting tuning slugs positioned about said first and said second elongated conductors respectively and movable along the respective axes of said conductors, and adjustable positioning means attached to said tuning slugs and extending through a wall of the cavity to provide simultaneous adjustment of the position of said tuning slugs.

2. A transmit-receive device comprising a plurality of conducting walls forming a cavity resonator, a first elongated conductor connected to a wall of the cavity and extending into the cavity, input means adjacent said first elongated conductor effective to apply input energy to said cavity, a second elongated conductor adjacent to said first conductor and connected to said wall of said cavity and extending into the cavity, output means adjacent said second conductor effective to derive output energy from said cavity, a nonlinear impedance connected between one of said conductors at its end extending into the cavity and the adjacent cavity wall effective to change abruptly in impedance value upon application of high voltage energy thereto, conducting means connected to one of said cavity walls and between said elongated conductors and extending into said cavity toward an opposite wall for a portion of the distance between said two last-mentioned cavity walls, a pair of conducting tuning slugs positioned about said first and said second elongated conductors respectively and movable along the respective axes of said conductors, and an adjustable positioning means attached to said tuning slugs and extending through a wall of said cavity to provide simultaneous adjustment of the position of said tuning slugs.
